(57) **CLAIM**

The ornamental design for a dart game, as shown and described.

DESCRIPTION

1. Dart game

1.1 : Front

1.2 : Back

1.3 : Right

1.4 : Left

1.5 : Top

1.6 : Bottom

The articles of the present designs are darts formed in a shape of Japanese shuriken, throwing star, and are for play by throwing the darts towards a target; a tip of each bladed portion of the present article has a bowl shape including a screw hole inside of the bowl shape; a dart tip can detachably be screwed into the screw hole at the tip of the bladed portion.
